Attorneys.

UNITED STATES PATENT OFFICE.

HACKLEY MORRISON, OF RICHMOND, VIRGINIA.

SAFETY DEVICE FOR PIPE-CUTTING MACHINES.

Application filed May 25, 1921. Serial No. 472,456.

To all whom it may concern:

Be it known that I, HACKLEY MORRISON, a citizen of the United States, residing at Richmond, in the county of Henrico and 5 State of Virginia, have invented certain new and useful Improvements in Safety Devices for Pipe-Cutting Machines, of which the following is a specification.

This invention relates to pipe cutting machines, and more particularly to machines of the type shown in my prior co-pending application S. N. 391,717, filed June 25, 1920.

In such prior application, I have shown an arm carrying the pipe supporting rolls, and 10 a weighted lever on which such arm is pivoted, such lever being arranged to yield when the pressure on the pipe exceeds a safe limit, so as to prevent injury to the machine and damage to the pipe.

20 While this automatically yielding arrangement is of great practical value, I find that it is desirable to superpose upon such automatic control, a manual control. It is, therefore, the object of the present invention to provide means whereby the pressure on the pipe can be manually relieved by the operator at will, without the necessity of depending wholly upon or waiting for the action of the automatic mechanism.

30 Specifically, the invention contemplates the provision of manual means for applying a force to the weighted lever, above mentioned, in a direction opposite to that in which the weight acts, such force serving 35 either to partially nullify the action of the weight, thus lessening the pressure, or to completely lift the weight, and with it, the lever, thus entirely relieving the pipe of pressure.

40 While I have shown the invention as applied to a machine having a weighted lever, as described, it will, of course, be understood that it is not limited to such application. The present improvements consist, broadly, 45 in providing a machine for cutting off pipe, having a power-operated feed, with manual means by which the pressure on the pipe may be quickly relieved, as occasion demands, at any stage of the cutting operation, should 50 the pipe fail to rotate, or should, for any other reason, the pressure tend to become excessive.

In order that the invention may be readily understood, reference is had to the accom-

panying drawing forming part of this specification, and in which:—

Fig. 1, is a vertical section through a pipe cutting machine, equipped with the present improvements, and

Fig. 2, is a fragmentary sectional plan 60 thereof on the line 2—2 of Fig. 1.

Referring to the drawings in detail, the machine herein illustrated by way of example, is of the same type as that shown in my prior co-pending application above referred to.

The machine comprises a bed 1 and a suitable supporting frame 2. 3 designates a cutter disc which is rigidly mounted upon a shaft 4, continuously rotated by suitable 70 means, (not shown). The pipe α to be cut, is supported on a pair of rolls 5 journaled in a cage 6^a carried by a lever 6. To the lever 6 is pivotally connected at 7, the lower end of a yoke 8, in the upper part of which is 75 adjustably mounted a block 9, such adjustment being effected by means of a hand-wheel 12. In the block 9 works an eccentric 10 carried by a power shaft 11, driven in any suitable way.

80 A bracket 13 is fixed to the bed of the machine and to the upper end of such bracket is pivoted at 15^a lever 14 on which a weight 17 is adjustably hung. Downward movement of the lever 14 is limited by a supporting bracket 18 secured to the bed of the machine.

85 Set into the lever 14 adjacent the pivot 15 is an adjustable screw 16 operated by a hand-wheel 16^a. The lower end of this screw bears 90 against the end of lever 6 and constitutes a fulcrum about which the lever 6 normally turns. The parts so far described, in construction and operation are the same as shown in my above identified co-pending application.

95 As fully explained in said application, the purpose of the above described construction, is to prevent damage to the pipe or the cutter. When the pressure on the pipe 100 becomes excessive, the reaction of the end of lever 6 on the screw 16, lifts the lever 14 slightly, thus permitting the supporting rolls 5 to yield and thus relieve the pressure.

105 I have found it desirable, however, to provide, in addition to the above described automatic device, manual means for relieving the pressure on the pipe at any time during

the cutting operation. To this end, I attach to the lever 14 a hand lever or arm extending forwardly to a point within easy reach of the operator, so that the operator, by grasping such hand lever, can at any moment, swing the lever 14 about its pivot and thus relieve the pressure on the pipe. In practice I prefer to provide a plurality of such hand-levers, one on each side of the cutter.

10 As shown in the drawing, these hand-levers, which are designated by the reference character 20, are secured to a cross bar 19, rigidly mounted upon the lever 14. In the construction shown in the drawing, the levers 20 are 15 provided with vertically extending threaded portions passing through the cross bar 19 and secured in position by lock nuts 20^a.

By means of these hand-levers, it will be seen that the operator can, when desired, 20 exert a force on the lever 14, tending to swing the same on its pivot 15 in a direction opposite to that in which the lever is urged by the weight. If such force is only slight, it will serve to partially counteract 25 the effect of the weight and thus lessen the pressure on the pipe; if the force is greater, it will serve to actually lift the weighted lever and thus entirely relieve the pipe of pressure.

30 Power operated feed pipe cutting machines of the disc type, have heretofore been open to the objection that the pipe is liable to be crushed by excessive pressure due to some defect or failure of the pipe to rotate properly, and by providing means under the control of the operator for instantly relieving the pressure on the pipe as above described, I am able to entirely overcome this objection and to reduce to a minimum the 35 chance of damage to the machine or the pipe.

While I have shown only a manual lever, and while I have used the word "manual" in the accompanying claims, it will of course, 45 be understood that by such term I also intend to include means operated by a foot pedal or the like, as well as by hand.

What I claim is:—

1. In a pipe cutting machine, the combination 50 with supporting rolls and a cutter disc, of power operated means for moving the one toward the other, in a path passing through the axis of the disc, to effect a cut, and manual means for regulating at will 55 during the cutting operation, the pressure on the work held between the rolls and cutter disc.

2. In a pipe cutting machine, the combination 60 with supporting rolls and a cutter disc, of power operated means for moving the one toward the other to effect a cut, and a manually operated pivoted lever for relieving, at any desired stage of the cut, the 65 pressure on the work held between the rolls and cutter disc.

3. In a pipe cutting machine, the combination with supporting rolls and a cutter disc, of power operated means for moving the one directly toward the other so as to 70 press the work and cutter disc together to effect a cut, and manual means for relieving the pressure on the work held between the rolls and cutter disc, should such pressure at any time become excessive.

4. In a pipe cutting machine, the combination with supporting rolls and a cutter disc, of power operated means for moving the one toward the other to effect a cut, automatic means for limiting to a predetermined possible maximum the pressure on 75 the work held between the rolls and cutter disc, and additional manual means for also relieving such pressure at will.

5. In a pipe cutting machine, the combination with cutting elements comprising 80 supporting rolls and a cutter disc, of an arm in which one of said elements is carried, automatic means for applying power to said arm to move the carried element toward the other, a movable pivotal support 85 for said arm, and manual means for moving said support.

6. In a pipe cutting machine, the combination with cutting elements comprising 90 supporting rolls and a cutter disc, of an arm in which one of said elements is carried, automatic means for applying power to said arm to move the carried element toward the other, a movable pivotal support for said arm, means for normally holding said support rigid, and manual means for moving 95 said support when required.

7. In a pipe cutting machine, the combination with cutting elements comprising 100 supporting rolls and a cutter disc, of an arm in which one of said elements is carried, automatic means for applying power to said arm to move the carried element toward the other, a normally rigid pivotal support for 105 said arm, said support having means permitting it to yield whenever the pressure on the rolls exceeds a predetermined amount, and manual means for causing said support 110 to yield whenever desired.

8. In a pipe cutting machine, the combination with cutting elements comprising 115 supporting rolls and a cutter disc, of an arm in which one of said elements is carried, automatic means for applying power to said arm to move the carried element toward the other, a normally rigid pivotal support for 120 said arm, said support having means permitting it to move whenever the pressure of the rolls exceeds a predetermined amount, and manual means for positively moving 125 said support as desired.

9. In a pipe cutting machine, the combination with cutting elements comprising 130 a cutter disc and supporting rolls, of an arm in which one of said elements is journaled,

a movably mounted support on which said arm is pivoted, power operated means for swinging said arm on its pivot, said means acting upon the arm at such a point that the pressure of the cutter disc against the work is opposed and sustained by the thrust of the arm against said movably mounted support, and manual means for moving said support when desired, to relieve such pressure.

10. In a pipe cutting machine, the combination

of cutting elements comprising a cutter disc and supporting rolls, of an arm in which one of said elements is journaled, a weighted lever on which said arm pivots, power operated means for moving said arm to effect a cut, and manual means for applying force to said lever, when desired, in a direction opposite to that in which the weight acts.

In testimony whereof I affix my signature.

HACKLEY MORRISON.
